UNITED STATES PATENT OFFICE.

ELKANAH H. WALKER, OF AUGUSTA, MAINE.

COIN-DELIVERING APPARATUS.

SPECIFICATION forming part of Letters Patent No. 544,330, dated August 13, 1895.

Application filed January 23, 1895. Serial No. 535,916. (No model.)

To all whom it may concern:

Be it known that I, ELKANAH H. WALKER, of Augusta, in the county of Kennebec and State of Maine, have invented certain new and 5 useful Improvements in Money-Changers or Change-Delivering Apparatus, of which the following is a specification.

My invention relates to new and useful improvements in a money-changer or change-delivering apparatus, and consists of the device hereinafter specified and claimed and illustrated in the accompanying drawings, forming a part of this specification.

Of the drawings, Figure 1 represents a top 15 view of the apparatus. Fig. 2 represents a front elevation of the same. Fig. 3 represents a section on the line 12, Fig. 1, looking to the left.

The object of my invention is to provide a 20 money-changer of simple and cheap construction, and to provide an apparatus which shall hold one coin of each denomination in a position to be easily grasped by the operator, and which shall, by one operation, when coins of 25 different denominations are withdrawn by the operator, cause one other coin of each denomination to take the place of those withdrawn.

The apparatus is constructed and operated 30 as follows:

a represent the walls of the box or casing, which is built or constructed upon a block or bottom *a'*, and has a false bottom *a''*. Inside the casing *a* are fixed a series of tubes 35 *b b*, of different sizes, constructed to hold the various denominations of coins. In the drawings I have shown tubes to hold half-dollars, quarters, dimes, nickels, and cents, but any other number or size of tubes may be used. 40 These tubes *b b* are preferably open in front, slots *c c* being cut in the front wall of the casing *a*, so that the coins in each tube can be seen from the front of the device, and I prefer to put scales *d d* on the front wall before 45 each slot *c* to mark the number of coins in each column, so that the amount of money in the apparatus can be readily calculated without emptying it.

The tubes *b b* are preferably affixed to the 50 front wall and top of the device and left open at the top, so that coins can readily be dropped into them. The tubes *b b* do not extend as

far as the false bottom *a''*, but are cut off a little more than the thickness of one coin above that bottom, so as to allow the bottom 55 coin of the column in the tube to be moved forward edgewise from the bottom of the pile, while the next coin above is prevented from moving edgewise by the tube in which it rests.

e represents a reciprocating plate or slide, 60 which moves back and forth between the false bottom *a''* and the bottoms of the tubes *b b*. The slide *e* is held in its normal position (shown in Figs. 1 and 3) by means of springs *f f*, which are attached to ears *g g* on the slide 65 *e* and to similar ears *h h* on the casing *a*. The slide *e* moves in slots *i* in the end walls *a* of the casing, and these slots *i* are so made as to control the forward movement of the slide *e* and prevent its being pulled farther forward than the normal position shown in Fig. 1. *j* represents a rod or bar having a knob *j'* on its front end, which is affixed to or made as a part of the slide *e* and passes through a hole in the front wall *a* of the casing. 70

The operation of the machine is as follows: The apparatus being empty, the tubes *b b* are filled by dropping the coins in at the top of the tubes. The various columns of coins are then supported by the slide *e*. The knob *j'* 80 is pushed and the slide *e* moves back from under the tubes *b*, and the columns of coins all drop down and rest on the false bottom *a''*. The knob *j'* is then released, and the springs *f f* bring the slide *e* forward into its normal 85 position, carrying with it one coin from the bottom of each pile. The front face of the slide *e* is of such form that when at the end of its forward movement and at rest each coin will project through the slots *c' c'* at the bottom of each tube almost, but not quite, one-half of its diameter, as shown in Fig. 1. Suppose now that the operator wishes to withdraw forty cents of change, he catches hold of and pulls out of the slots *c' c'* a quarter, 90 a dime, and a nickel. Then he pushes in the knob *j'*, and on the retraction of the slide *e* the quarter, dime, and nickel piles all drop down onto the false bottom *a''*, while the half-dollar and cent columns, being supported 95 by the coins already projected through the slots *c'*, remain stationary. On the release of the knob *j'* the slide *e* will be moved forward and will bring with it the lowermost quarter, 100

dime, and nickel, and will come to rest with its front edge just touching the half-dollar and cent previously projected. It will thus be seen that the place of each coin withdrawn is filled at each pressure of the knob j' , and if more than one coin be withdrawn their places are filled simultaneously by one push of the knob.

I do not limit myself absolutely to the 10 tails of construction herein shown and described, but may use any equivalent device. For instance, the base a' need not be solid, but may be a casing like the upper part. I prefer, however, to have part of the casing or 15 structure under as well as above the false bottom a'' , in order that when the apparatus is used on an ordinary table there may be room under the projected coins for the finger or thumb of the operator.

20 In lieu of the springs $f f$, I may use any equivalent device—such as rubber bands or the like; or I may reciprocate the slide e in any other suitable manner.

For the sake of clearness I have shown the 25 device empty, except in Fig. 1, where one coin in each tube is shown in its projected position.

I claim—

1. In a change-delivering apparatus, the 30 combination of a series of tubes, holding coins

of different denominations, and a reciprocating plate moving across the ends of said tubes and by its operation keeping one coin from each tube projected in a position to be grasped by the operator, substantially as described. 35

2. In a change-delivering apparatus, the combination of the casing a , tubes $b b$ arranged near the front of said casing, and the reciprocating slide e fitted to project from said tubes and through the front of the casing, by one operation, one coin from each or from any number of said tubes, substantially as described. 40

3. In a change-delivering apparatus, the combination of the casing having a bottom 45 plate a'' , the coin tubes $b b$, supported above said bottom plate, the reciprocating slide e moving between said tubes and said bottom plate and which is capable of operating upon the coins in all of said tubes at one time, and 50 means whereby said slide can be moved back and forth, substantially as described.

In testimony whereof I have signed my name to this specification, in the presence of two subscribing witnesses, this 19th day of 55 January, A. D. 1895.

ELKANAH H. WALKER.
